DESIGN FOR A VELOCIPED FRAME MEMBER

Harold L. van Doren, Toledo, and John G. Rideout, Perrysburg, Ohio, assignors to The American-National Company, Toledo, Ohio, a corporation of Ohio

Application February 5, 1936, Serial No. 60,993

Term of patent 7 years

To all whom it may concern:

Be it known that we, Harold L. van Doren and John G. Rideout, citizens of the United States of America, residing at Toledo and Perrysburg, in the counties of Lucas and Wood, respectively, and State of Ohio, have invented a new, original, and ornamental Design for a Velocipede Frame Member, of which the following is a specification, reference being had therein to the accompanying drawing forming a part thereof, wherein:

Figure 1 is a perspective view of a velocipede frame member showing our new design;

Figure 2 is a side elevation thereof;

Figure 3 is a top plan view thereof;

Figures 4 and 5 are cross sectional views taken on the lines 4-4 and 5-5, respectively, of Figure 2.

We claim:

The ornamental design for a velocipede frame member substantially as shown.

HAROLD L. VAN DOREN.
JOHN G. RIDEOUT.
